WELLS H. CLAUSSEN, OF SEATTLE, WASHINGTON, ASSIGNOR TO APPLE VENDER CO., OF SEATTLE, WASHINGTON, A CORPORATION OF WASHINGTON

DESIGN FOR A CASING FOR FRUIT VENDING MACHINE

Application filed February 24, 1931. Serial No. 38,801. Term of patent 14 years.

To all whom it may concern:

Be it known that I, WELLS H. CLAUSSEN, a citizen of the United States, residing at Seattle, in the county of King and State of Washington, have invented a new, original, and ornamental Design for Casing for Fruit Vending Machine, of which the following is a specification, reference being had to the accompanying drawing, forming part thereof.

The figure is a front view in isometric perspective, showing my new design which is uniformly the same on all sides except for the coin controlled device and fruit vending opening at the front.

I claim:

The ornamental design for a casing for fruit vending machines, as shown and described.

WELLS H. CLAUSSEN.
